UNITED STATES PATENT OFFICE.

JACQUES DUCLAUX, OF PARIS, FRANCE, ASSIGNOR TO FABRIQUE DE SOIE ARTIFICIELLE DE TUBIZE, SOCIETE ANONYME, OF BRUSSELS, BELGIUM.

METHOD FOR THE CONCENTRATION OF ACETIC ACID.

No Drawing. Application filed March 31, 1924, Serial No. 703,262, and in Germany April 4, 1923.

This invention relates to an improved method for the concentration of diluted acetic acid. As it is well known, aqueous solutions of acetic acid are obtained in numerous 5 industrial operating methods. Solutions of this kind are generally not adapted for immediate use or sale on account of their dilution. Therefore it is often necessary to increase the concentration of the acetic acid 10 which is contained therein or even to convert the solution into glacial acetic acid.

Acetic acid and water can be separated from each other by rectifying operations. Such operations however as it is known, 15 have not the same efficiency which they possess in other cases, as for instance in the separation of alcohol from water. The ordinary rectifiers which are generally industrially used cannot secure a complete 20 separation from acetic acid and water and cannot bring all of the acid to the glacial state.

According to this invention, this result is secured by adding to the mixture or aqueous 25 solution of acetic acid, acetone oil having a suitable boiling point.

The acetone oils which are obtained as residual products, in the rectification of ordinary acetone, contain a great number of 30 elements, the boiling points of which vary from 80° to above 200° C. More particularly they contain elements the boiling point of which is about 100° C. such as di-ethyl-ketone, methyl-propyl and methyl-isopropyl-ketone.

When a mixture of water, acetic acid, and such ketones is distilled, the latter are first distilled at the beginning of the operation in such a manner that the said acid becomes 40 gradually more and more concentrated in the residue. If the proportions are exactly calculated, there remains only in the distilling apparatus acetic anhydride after all of the water has been expelled. If, on 45 the contrary, the proportions are not exactly calculated, as is generally the case in practice, there remains finally acetic acid and the ketones which can be separated by a rectifying operation. The only condition 50 to observe in order that the said rectifying operation may be possible, is that a sufficient difference must exist between the boiling temperature of the acetic acid (117° C.) and that of the ketone which is employed. It 55 is for this reason that the use of products

having a boiling point of about 100° C. is to be preferred, but other products which are less volatile than acetic acid, can also be employed such as for instance mesityl-oxide, the boiling point of which is about 60 130° C.

The ketones, which are here referred to, have only a slight solubility in water. The vapors which are distilled, give when they are condensed, a liquid which separates into 65 two layers, the lower layer of which is water. The upper layer is formed by the ketone which may be returned into the distilling apparatus to continue the same cycle. Under these conditions, the quantity of 70 ketone which is necessary for the operation is only that which is always circulating and which may be very small.

The dehydration of the acetic acid by the above described method may be carried out 75 in a continuous manner. As an example in a rectifying apparatus, one of the intermediary plates, which will be conveniently chosen in practice, will be fed simultaneously with the liquid which is to be concentrated, and with the ketone in such quantities that the ketone and the water will be exactly in the proportions in which they are passing when they are distilled together. If these conditions are observed, the 80 lower plates of the column of the rectifying apparatus will only collect anhydrous acetic acid.

The constituents of the acetone oils, the use of which has just been described, may 85 be employed either in a pure state or in the form of mixtures. These products do not act chemically one upon another, but the process is based upon the following physical properties of these constituents. 90

They form with water, a system having 95 a boiling point which is lower than the boiling point of the constituents.

Their boiling point is sufficiently high and their molecular weight sufficiently low, 100 so that the vapor which is produced by the system will contain a considerable proportion of water vapor; the proportion of water and other substance being determined by the physical constants thereof in the well-known fashion of constant boiling mixtures.

Further, the said constituents do not form with acetic acid a system, the boiling point of which is lower than either of the boiling points of the said constituents. Thus, a mix- 110

ture of acetic acid and acetone oils (boiling at 100° C.) has a boiling point which varies during the distillation from 100° C. to 117° C., but is never lower than 100°, while a mixture of acetic acid and acetone oil (boiling at 130° C.) has a boiling point which varies during the distillation from 117° C. to 130° C., but is never lower than 117° C. In the first case it is the oil which passes over first and in the second case it is the acid, but in neither case is the boiling point lower than that of the two constituents which is the more volatile. The boiling point of these constituents is, in consequence, sufficiently different from the boiling point of acetic acid so that the separation can be effected by distillation and they are not decomposed under the conditions of operation.

Other constituents may be substituted for acetone oils; it is only necessary for this object that the constituent which is used, possesses the properties which have been enumerated hereabove; but any constituent which does not comply with these properties may be excluded.

What I claim is:

1. The method of concentrating acetic acid in water solution which comprises mixing with the solution a substance, substantially insoluble in water, which forms a constant boiling mixture sufficiently different from the boiling point of acetic acid to permit of fractionation with water but not with acetic acid, and subjecting the mixture to fractional distillation, whereby the constant boiling mixture of water and other substance is removed and substantially anhydrous acetic acid remains behind.

2. The method of concentrating acetic acid in water solution which comprises mix-

ing a water insoluble acetone oil therewith of a constitution which is water insoluble, but which forms a constant low boiling mixture with water but not with acetic acid sufficiently different from the boiling point of acetic acid to permit of fractionation, and separating the mixture of water and acetone from the acetic acid by rectification.

3. The method of concentrating acetic acid in solution which comprises mixing with the solution, a ketone which is substantially water insoluble and forms a constant low boiling mixture with water and not with acetic acid, having a boiling point lower than the boiling point of acetic acid, heating the mixture to the constant boiling point of the mixture, removing all the vapor of the constant boiling mixture, heating the residue to the boiling point of the ketone, and removing the vapor of the ketone, leaving substantially pure anhydrous acetic acid in the still.

4. The method of concentrating solutions of acetic acid, the said method consisting in adding, to the solution, acetone-oils having a boiling point of about 100-130° C. and then subjecting the mixture to a rectifying operation, whereby the acetic acid becomes concentrated and is obtained as concentrated acetic acid.

5. The method of concentrating aqueous solutions of acetic acid, the said method consisting in adding to the solution, acetone-oils having a boiling point of about 100-130° C. and then subjecting the mixture to a continuous rectifying operation, whereby concentrated acetic acid is obtained.

In testimony whereof I have affixed my signature.

JACQUES DUCLAUX.
